(57) CLAIM

The ornamental design for a see-through theme vessel table, as shown and described.

DESCRIPTION

FIG. 1 is a top perspective view of the see-through theme vessel table, showing my design.

FIG. 2 is a side elevation view thereof.

FIG. 3 is a top plan view thereof.

FIG. 4 is a bottom plan view thereof; and,

FIG. 5 is a top perspective view thereof showing display items in the theme vessel below the see-through table top, the showing of the display items being for illustrative purposes only and forming no part of the claimed design.
